UNITED STATES PATENT OFFICE.

SAMUEL JAMES HUNGERFORD, OF WINNIPEG, MANITOBA, CANADA.

SUPERHEATER.

1,124,446.

Specification of Letters Patent. Patented Jan. 12, 1915.

Application filed September 29, 1913. Serial No. 792,415.

To all whom it may concern:

Be it known that I, SAMUEL JAMES HUNGERFORD, of the city of Winnipeg, in the Province of Manitoba, Canada, have invented certain new and useful Improvements in Superheaters, of which the following is the specification.

The invention relates to improvements in superheaters especially designed for installation in locomotive engines and the object of the invention is to provide an efficient simply constructed superheater which can readily be installed in locomotive engines of present design, a particular feature of the invention residing in the construction which permits the superheater parts to be easily and quickly installed, removed or replaced and also allows an easy entrance to all joints where a possible leakage of steam might occur.

Further objects of the invention are to provide a superheater wherein the troubles arising from expansion and contraction of the parts has been reduced to a minimum and also to provide a superheater in which the superheating tubes can be readily approached and cleaned.

With the above objects in view the invention consists essentially in the arrangement and construction of parts hereinafter more particularly described and later pointed out in the appended claims.

Figure 1 represents a longitudinal sectional view through the front end of a locomotive boiler showing my superheater installed. Fig. 2 represents a vertical cross sectional view through the front end of the locomotive boiler, certain of the auxiliary headers being shown in vertical section. Fig. 3 represents a side view of one of the auxiliary headers. Fig. 4 represents a vertical sectional view through one of the auxiliary headers. Fig. 5 represents a detailed perspective view of a portion of one of the superheating tubes. Fig. 6 represents an enlarged detailed front view of the main top header detached, part being shown in vertical section. Fig. 7 represents an enlarged detailed front view of the bottom main header detached, part being shown in vertical section. Fig. 8 represents an enlarged detailed vertical sectional view through a portion of the top header and a portion of one of the auxiliary headers showing the manner of forming the joint between these parts. Fig. 9 is an enlarged detailed vertical

sectional view through a portion of the bottom header and a portion of one of the feed pipes showing the joint formed between these parts.

In the drawings like characters of reference indicate corresponding parts in each figure.

1 represents a locomotive boiler, 2 the front tube sheet and 3 the boiler flues.

5 represents the smoke stack, 6 and 7 the petticoat pipes, 8 the exhaust pipe, 9 the smoke box and 10 the smoke box screen.

11 represents the dry steam pipe of the boiler, which steam pipe passes in the usual way above the flues 3 and through the tube sheet 2.

The above parts are all of ordinary construction, being found in locomotives of present design and they form no part of my invention.

I might here explain that my superheater is installed to superheat the steam from the dry steam pipe prior to passing it to the engine cylinders.

12 and 13 are two similar angle iron supports secured to the sides of the smoke box in any suitable way and carrying oppositely disposed top and bottom pairs of brackets 14 and 15, and 16 and 17 which support the top and bottom main headers shortly described.

18 represents a horizontally disposed main top header carrying centrally an elbow 18' fitted with an outstanding flange 18² supplied with similar bolt holes 18³.

19 represents a thimble carried by the tube sheet 2 and receiving the forward end of the dry steam pipe 11. This thimble is supplied also with an outstanding flange 19' and has the forward end thereof coned at 19² and fitting into the adjoining bevelled edge of the elbow.

20 is a ring receiving the inner end of the thimble and bearing against the inner face of the tube sheet.

20' are bolts passing through the ring, tube sheet and flanges 19' and 18² and fitted with nuts 20² and 20³, the nut 20² screwing up against the front face of the flange 19' while that 20³ screws up against the forward face of the flange 18².

20⁴ is a packing ring inserted between the flange 19' and the tube sheet.

The above construction provides an especially tight joint between the steam pipe and the tube sheet and also between the

thimble and the elbow and permits the elbow and consequently the main top header to be removed while still maintaining a tight joint between the thimble and the 6 tube sheet.

10 The ends of the header bear on the upper pair of brackets 14 and 15 and are permanently secured to the supports 12 and 13 by suitably located bolts 21. The said header is provided on the front side with a series of openings 22, these openings being arranged to permit the dry steam to pass into the saturated steam auxiliary header shortly referred to. In the present instance there 15 are six of these openings 22, one for each saturated steam auxiliary header.

23 is a bottom main header which header is located in a more or less horizontal position at a point somewhat below the top 20 header and has the ends thereof resting on the top of brackets 16 and 17 and fastened by suitable bolts 23' to the supports 12 and 13.

25 The bottom header is supplied on the forward side with a series of similar openings 24 adapted to register with the ducts of the superheated steam auxiliary headers later described and it is formed further with a 30 pair of similar, elbows 25 provided with outstanding flanges 25' connected by bolts 25' to similar outstanding flanges 27' and 28' presented by the feed pipes 27 and 28, the feed pipe being designed to distribute the superheated steam from the bottom 35 header into the cylinders of the engine (not shown). The adjoining faces of the elbows and feed pipe are coned out to receive a gasket 26 which forms a particularly effective steam tight joint between these 40 parts when the bolts are tightened up.

29 represent similar saturated steam auxiliary headers and 30 represent similar superheated steam auxiliary headers which headers carry the superheating coils later 45 referred to and are interposed between the main top and bottom headers. In the present instance there are six saturated steam auxiliary headers. These auxiliary headers are all constructed in the same manner and 50 as shortly described with the exception that those 29 are what might be termed a right and those 30 a left hand construction, that is, formed complementary to each other. Each auxiliary header provides an interior 55 steam chamber 32 and is supplied on the inner side with a series of openings 33, 34 and 35 and on the outer side with a further series of directly opposing screw threaded openings 36, 37 and 38, these latter openings 60 being designed to receive removable screw plugs 39. They are each fitted with a duct 40 which is designed to register with one or other of the openings in the top or bottom header as the case may be. A single lug 41 65 extends from one end of each section while

the body portion thereof carries two similar projecting lugs 42 and 43, the lugs being arranged so that when two complementary headers are brought together the single lugs are slidably received within the double 70 lugs. When the complementary headers are so fitted they are fastened together by pins 44 and 45, the pins being carried by the double lugs and passing through elongated slots 46 presented by the single lugs. 75

The front faces of the top and bottom main headers are faced up adjoining the openings 22 and 24 and are coned out as indicated at A while the adjoining faces of all the auxiliary headers are reamed out as 80 indicated at B at the entrance to the ducts 40.

Joint rings 47 are inserted between the auxiliary and main headers which joint rings are formed on the one side with an abrupt shoulder which receives the auxiliary 85 header and at the other side with a beveled face which fits into the cone face A. When the rings are inserted the auxiliary headers are fastened to the main headers by studs 48 and 48' which pass through suitably located 90 openings supplied on the auxiliary headers and into the walls of the main header.

It is here to be noticed that the adjoining faces of the complementary auxiliary headers carry projecting tongues 49 and 50 which 95 space the bodies of the headers apart when they are assembled and provide an open space between them.

51 represent superheating coils passing 100 into the boiler flue 3 and having their forward ends connected with the auxiliary headers. In the present instance each pair of auxiliary headers is shown as carrying three distinct coils, said coils having each 105 an end connected with the steam chamber of one of the saturated steam auxiliary headers and an end connected with the steam chamber of one of the superheated steam auxiliary headers. Accordingly a passage is 110 formed for the steam through a saturated steam auxiliary header to a superheated steam auxiliary header by way of the coils.

With my device installed the dry steam is 115 passed from the dry steam pipe 11 directly into the top main header from which it is distributed into the saturated steam auxiliary headers, the steam entering the headers through the openings 22 and the ducts 40. From the saturated steam auxiliary 120 headers the steam passes through the coils 50 where it is superheated and is returned to the superheated steam auxiliary headers. It is passed from these headers through the ducts 40 and the openings 24 to the bottom main header from which it is led to the locomotive cylinders through the elbows 25 and the pipes 27 and 28. 125

It will be seen that by forming the auxiliary headers as shown that the expansion 130

and contraction of the main and auxiliary headers is taken care of and there is no side strain brought on the joints formed between the auxiliary and main headers. Accordingly there is little possibility of these joints leaking during service. Further it will be seen that any pair of auxiliary headers can readily be taken out for repairs without molesting in any way any other of the auxiliary headers. This saves both time and labor which is a very important consideration in locomotive construction. If at any time it is required to tighten the joint formed between the coils and the auxiliary headers this can be readily accomplished by removing the adjoining screw plug 39.

What I claim as my invention is:—

1. In a superheater the combination with a main top header and a main bottom header, of complementary pairs of saturated and superheated steam auxiliary headers, the saturated steam auxiliary headers being detachably secured to the top header and the superheated steam auxiliary headers being detachably secured to and opening to the interior of the bottom header, means spacing the auxiliary headers of each pair, means slidably connecting the auxiliary header of each pair and extending superheating coils connecting the saturated steam auxiliary header of each pair with the superheated steam auxiliary header of that pair, as and for the purpose specified.

2. In a locomotive inspirator the combination with a dry steam pipe, the boiler flues and the cylinder feed pipes of the locomotive, of a main top header communicating with the dry steam pipe, a main bottom header communicating with the feed pipes, complementary pairs of saturated steam and superheated steam auxiliary headers providing interior steam chambers, the saturated steam auxiliary headers being detachably secured to the top header and opening to the interior thereof and the superheated steam auxiliary headers being detachably secured to the bottom header, means spacing the auxiliary heads of each pair, pins slidably connecting the auxiliary heads of each pair and extending superheating coils connecting the auxiliary headers of each pair, said coils opening to the chamber thereof and extending within the boiler flues, as and for the purpose specified.

3. In a superheater the combination with a main top header and a main bottom header, of similar pairs of saturated and superheated steam auxiliary headers, the saturated steam auxiliary headers being detachably secured to and opening to the interior of the top header and the superheated steam auxiliary headers being detachably secured and opening to the interior of the bottom header, extending superheating coils connecting the saturated steam auxiliary headers with the adjoining superheated steam auxiliary headers of each pair and removable screw plugs carried by the auxiliary headers and disposed directly opposite the connections of the coils with the auxiliary headers, as and for the purpose specified.

4. In a superheater, the combination with a main top header and a main bottom header, said headers having suitably spaced cutout openings located in the front face thereof and communicating with the interior thereof, of similar pairs of saturated and superheated steam auxiliary headers provided with interior steam chambers communicating through suitable ducts to the exterior of the auxiliary headers, joint rings inserted within the openings in the main top header and ducts of the saturated steam auxiliary headers, said rings being supplied with outstanding portions appearing between the top main header and the saturated steam auxiliary header, joint rings received within the openings of the main bottom header and the ducts of the superheated steam auxiliary headers, said rings having extending portions interposed between the adjoining faces of the main bottom header and the auxiliary saturated steam header, studs connecting the auxiliary headers detachably to the main top and bottom headers and superheating coils connecting the saturated steam auxiliary headers with the adjoining superheated steam auxiliary headers of each pair, as and for the purpose specified.

Signed at Winnipeg this 1st day of August 1918.
